United States Patent Office.

GEORGE W. RAY, OF SPRINGFIELD, MASSACHUSETTS.

Letters Patent No. 63,177, dated March 26, 1867.

IMPROVEMENT IN MACHINES FOR EMBOSSED ARTICLES OF WEARING APPAREL.

The Schedule referred to in these Letters Patent and making part of the same.

TO ALL WHOM IT MAY CONCERN:

Be it known that I, GEORGE W. RAY, of Springfield, in the county of Hampden, and State of Massachusetts, have invented a new and useful Improvement upon Machinery for Embossing Paper for Articles of Wearing Apparel; and I do hereby declare that the following is a full, clear, and exact description of the construction and operation of the same, reference being had to the annexed drawings, making a part of this specification, in which—

Figure 1 is a longitudinal elevation.

Figure 2 is a transverse section through line A B of fig. 1.

Figure 3 is a plan of a metallic plate, covered with a woven fabric; and

Figure 4 is a section of fig. 3 through line a a.

The nature of my invention consists in the construction of apparatus for using a woven fabric under a heavy pressure, for the purpose of embossing paper, either before or after its conversion into articles of wearing apparel, by forcing the woven fabric into the surface of the paper, so that the paper may present an exact negative of the fabric, instead of using metallic dies, said fabric, or its production, forming the subject of my application filed March 28, 1865.

In the drawings, A' A' is a cast-iron frame, firmly braced and held by the rods b b, in which frame is an aperture, g, made to receive the sliding boxes e e, which are the bearings of the rolls c d. The upper roll c has its bearings or boxes upon the upper side, and it rests upon and communicates its motion to the lower roll, and screws, f f, are provided to force the upper roll c down upon the lower roll d when it is desired to obtain greater pressure. The upper roll c is covered with any desired woven fabric which I wish to imitate. It may be well to first varnish over the surface of the metallic roll c with a thin solution of shellac, or its equivalent, and before it is entirely dry stretch over its surface the fabric to be imitated, and bring the two ends of the fabric together, so that they shall be exactly even and level upon the face of the roll. The upper roll c is then forced down upon the lower roll d by means of the screws f f, so that there may be sufficient pressure, and motion is communicated by means of the pulley i. The woven fabric, when bedded and held firm by the shellac, becomes perfectly solid and hard, and becomes in itself a die, from which many thousand impressions can be taken without injury to the fabric. It is obvious that, instead of covering the roll c, the fabric might be carried around the roll c and over an auxiliary roll placed above it, in the form of an endless belt, or it might be a long piece of goods, reeled from one roll, carried between the embossing rolls c d, and reeled upon another roll upon the other side. To secure easy manipulation of the paper and a good impression, however, it is best that the fabric should be as solid as possible. I also cover a metallic plate, p, with any fabric which I wish to imitate, on either one or both sides, and when I emboss paper in the sheet, can (when the plate is covered on both sides with the fabric) emboss two or three sheets at once, by placing two sheets faced to the covered plate, one on each side, and still another faced to the covered roll, and then pass the covered plate p, with the paper, between the rolls.

When embossing paper in the roll, or in a continuous strip or sheet, I place the roll of paper upon one side of the machine, in such position as that it shall be unrolled easily and freely, and pass it between the rolls without using the covered plate, and as fast as it passes through and is embossed, roll it up upon another roller on the other side of the machine. After starting in this way it needs no particular attendance until completed. The rapidity with which I can change from one quality or kind of fabric to another (as the roll can be covered with any desired fabric in ten minutes) obviates the expense and sometimes perplexing delays of manufacturing and waiting for metallic dies, and, as many thousand sheets can be embossed from one piece of goods without materially injuring it, the manufacture of imitated cloth goods from paper, which article is now becoming extensively used and introduced in commerce, is very much cheapened and facilitated.

I do not claim to emboss by means of rolls alone, as this has been practised heretofore, but in doing so it has been necessary to have the rolls engraved, either one or both of them, a practice which involves much time, labor, and expense, and even then it is found impossible to make an engraved roll which will produce an exact and perfect negative imitation of the fibre and figure of a fabric, especially the finer qualities of linen and muslin; but by my method I can produce an exact and perfect imitation of any fabric, however fine or coarse, so that even the twist of the thread may be seen in the impression by the aid of a glass. Neither do I claim

to emboss by means of electrotyped or any other metallic dies, as I am aware that this has also been done heretofore by various similar means and devices; but, having described my invention, what I do claim as new, and desire to secure by Letters Patent, is—

1. The roll *c*, covered, or partially covered, with a woven fabric, in combination with the roll *d*, substantially as described and for the purpose set forth.
2. The plate *p*, in combination with the roll *c* and roll *d*, one or more of these parts being covered, all substantially as described and for the purpose set forth.

GEORGE W. RAY.
